(57) **CLAIM**

The ornamental design for a gem microscope base, as shown and described.

DESCRIPTION

FIG. 1 is a perspective view of a gem microscope having a gem microscope base;

FIG. 2 is a perspective view of a gem microscope base;

FIG. 3 is a top view of the gem microscope base;

FIG. 4 is a front end view of the gem microscope base;

FIG. 5 is a right side view of the gem microscope base; and,

FIG. 6 is a rear end view of the gem microscope base.

The broken line showing of the microscope is for illustrative purposes only and forms no part of the claimed design.
